DESIGN FOR A SHOE

John J. Walsh, St. Louis, Mo.

Application April 21, 1947, Serial No. 138,524

Term of patent 14 years

(Cl. D7—7)

To all whom it may concern:

Be it known that I, John J. Walsh, a citizen of the United States, residing in the city of St. Louis, State of Missouri, have invented a new, original, and ornamental Design for a Shoe, of which the following is a specification, reference being made to the accompanying drawing, forming a part thereof, in which Figure 1 is a top plan view of a shoe embodying my new design; Figure 2 is a side elevational view thereof; Figure 3 is a rear elevational view thereof; and Figure 4 is a front elevational view thereof.

I claim:

The ornamental design for a shoe, substantially as shown.

JOHN J. WALSH.
